UNITED STATES PATENT OFFICE.

WILLIAM DOWNS, OF ORANGE, NEW JERSEY.

FUEL-ECONOMIZER FEED-WATER HEATER.

SPECIFICATION forming part of Letters Patent No. 708,699, dated September 9, 1902.

Application filed May 7, 1902. Serial No. 106,272. (No model.)

To all whom it may concern:

Be it known that I, WILLIAM DOWNS, a subject of the King of Great Britain, and a resident of Orange, in the county of Essex and State of New Jersey, have invented certain new and useful Improvements in Fuel-Economizer Feed-Water Heaters, of which the following specification is a full and clear description.

10 This invention relates to that class of apparatus commonly known as "Green's fuel-economizer," which is used to heat the water fed into steam-boilers or otherwise utilized by abstracting the heat from the products of 15 combustion after they have left the boiler.

The invention comprises certain changes and arrangements of the parts and construction of the headers whereby it is possible to economize space, more readily dispose of the 20 soot which collects on such apparatus, and particularly to more easily and readily adjust the disarranged or broken parts of the apparatus.

In the accompanying drawings, Figure 1 is 25 a side elevation of a fuel-economizer embodying my improvement. Fig. 2 is an end view of the same. Fig. 3 is a detached top view of two headers enlarged. Fig. 4 is a section of Fig. 3 on the line $x-x$. Fig. 5 is a side 30 view of Fig. 3.

In my reference to the parts of the device and description of my improvements in this specification I designate the different parts as follows:

35 A is a longitudinal inlet supply-pipe provided with means for connection to a source of a supply of water.

B B are horizontal pipes forming headers, known as the "bottom boxes."

40 C C are upright circulating-tubes, connecting the bottom boxes with the top boxes D D, which are connected to a general outlet pipe F.

H is a housing or wall, usually of brick, 45 closing the bottom boxes and the upright circulating-tubes.

J J are scrapers adapted to slide up and down the vertical tubes to remove the soot from their exterior surfaces.

50 K represents the soot-pit, in which the soot collects after being disengaged from the tubes.

In this class of fuel-economizer it is necessary to have the apparatus as compact as possible in order to save space. The headers B 55 are placed parallel with each other and as close together as the proper working of the scrapers will permit. Each header B has the required number of bosses or collars I I to provide for a junction with the upright circulating-tubes C C. These collars come quite close to each other, and one of the objects of my invention is to enable the upright tubes to be placed closely together, while at the same time ready access may be had to the 60 space between them at their bases. This is an important point, as the scrapers are apt to get clogged or broken during use, and by my improvement the great inconvenience of working about them with a long stick or taking the apparatus to pieces to remove the 65 broken part is avoided. In order to remove parts of the scrapers which may become loose or get broken, a passage-way between the 70 upright tubes and the inclosing wall is sometimes used and the broken parts of the scrapers removed or new parts adjusted from the side with the aid of a stick or rod.

75 In my improvements in fuel-economizers I construct the bottom boxes of an improved 80 form, so that I am able to make all repairs of the scrapers from the soot-pit. If the bottom boxes were simply made smaller in diameter, it would weaken them and interfere with the flow of water and the proper connections with the circulating-pipes, and I therefore leave the headers B of the normal 85 size at the point of junction with the vertical circulating-pipes C and make the bosses L L on the headers of the size required for 90 such diameter of pipe. Between the bosses I change the construction of the headers and flatten the sides so as to contract the diameter laterally, as shown in Fig. 3. While thus contracting the diameter of the header laterally at this point, I prefer to leave the vertical dimension as large as possible, so that the section assumes an oval shape at this point. In this way the area for flow of water through the header is made ample and also 95 the header is made stronger to carry the weight of the circulating-pipes which comes upon it. This transverse strength may be further increased by the addition of strength-

ening-ribs 2 2 between the bosses and by a continuous rib 3 on the bottom of the header, extending its whole length to the points where it is supported on the walls at 4 4. The flattening and deepening of the header in the manner last described also have the effect of exposing a larger surface to the action of the hot gases, thereby increasing the absorption of heat.

10 By means of this construction of header I obtain a large free space between adjacent headers at those points which are between the bases of each pair of upright pipes. This space is such as to allow access from the soot-pit with the hand or otherwise for the purposes of working on or adjusting the scraper mechanism. The opening is also of sufficient size to pass a scraper up or down through it when it is required to make changes. The 15 larger opening also facilitates the passage to the soot-pit of the particles of soot disengaged from the circulating-tubes by the scrapers.

15 What I claim as my invention, and desire to secure by Letters Patent, is—

20 1. In a fuel-economizer of the character specified, the combination of a series of top boxes, outlet and supply pipe, and vertical

circulating-tubes, with a series of lower headers arranged parallel, said lower headers having bosses to receive the vertical tubes, and also having laterally-contracted portions between the bosses, substantially as and for the purpose as shown and described.

2. In a fuel-economizer of the character specified, a series of headers with bosses to receive vertical tubes, said headers being contracted laterally and extended vertically in the portion between the bosses, in combination with a supply-pipe, vertical circulating-tubes, top boxes; and outlet-pipe substantially as and for the purposes shown and described.

3. In a fuel-economizer of the character specified, a series of headers with bosses to receive vertical tubes, said headers being contracted laterally and provided with ribs and extended vertically in the portion between the bosses, in combination with a supply-pipe, vertical circulating-tubes, top boxes, and outlet-pipe, substantially as and for the purposes shown and described.

WILLIAM DOWNS.
